(57) **CLAIM**

The ornamental design for a manifold with two sided ports, as shown and described.

DESCRIPTION

FIG. 1 is a left side top front perspective view of the present design a manifold with two sided ports.

FIG. 2 is a right side top front perspective view of the manifold with two sided ports shown in FIG. 1.

FIG. 3 is a left end elevational view of the manifold with two sided ports shown in FIG. 1; and,

FIG. 4 is a right end elevational view of the manifold with two sided ports shown in FIG. 1.

The ports are repeated at regular intervals throughout the length of the article.

The cut away portion in the drawings indicates the appearance of any portion of the article between the cut away lines forms no part of the claimed design.
